CONVEYER

Nils D. Levin, Columbus, Ohio, assignor to The Jeffrey Manufacturing Company, a corporation of Ohio

Original application March 6, 1937, Serial No. 129,446. Divided and this application December 3, 1938, Serial No. 243,810

3 Claims. (Cl. 198—168)

This invention relates to a conveyer which is particularly adapted to form a part of a system for removing dirt bands or slate from a coal mine vein.

An object of the invention is to provide an improved type of conveyer which can be operated to discharge material over either end thereof.

A further object of the invention is to provide a conveyer adapted to be positioned adjacent the arcuate face of a coal mine room.

A further object of the invention is to provide an improved arcuate conveyer with mechanism to drive the conveying chain thereof and maintain it in proper tension at all times.

A further object of the invention is to provide an improved conveyer with means to guide the chain into stationary guideways particularly where the conveyer is of an arcuate construction.

Other objects of the invention will appear hereinafter, the novel features and combinations being set forth in the appended claims.

In the accompanying drawings,

Fig. 1 is a somewhat diagrammatic plan view showing a system including the conveyer comprising my invention as employed in a coal mine;

Fig. 2 is an enlarged plan view showing one end of the central or face conveyer of my invention and the receiving end of one of the wing conveyers;

Fig. 3 is a side elevational view of a detail showing particularly the drive means for the central or face conveyer;

Fig. 4 is a side elevational view of one of the wing conveyers;

Fig. 5 is a side elevational view of an end of the central or face conveyer;

Fig. 6 is a transverse sectional view taken on the line 6—6 of Fig. 3 looking in the direction of the arrows;

Fig. 7 is a detail view partly in section showing particularly the means for driving one of the wing conveyers from the central or face conveyer; and

Fig. 8 is a sectional view taken on the line 8—8 of Fig. 7 and showing one of the one-way drive clutches for one of the wing conveyers.

This application is a division of my application for a Mining system, Serial No. 129,446, filed March 6, 1937, patented August 15, 1939, Patent No. 1,169,424 which claims the conveyer herein claimed in combination with other elements which form the complete system, or at least a part thereof.

The conveyer herein claimed is disclosed as a

part of the complete system claimed in the above mentioned application, as above set forth. It is to be understood, however, that this conveyer may be used independently of the complete system. Referring to the accompanying drawings there is illustrated a system for removing bands of foreign material from a vein of coal of which the conveyer forming the subject matter of this application is an important part.

- 10 As shown in Fig. 1, a track-mounted kerf-cutting mining machine 12 travels along the central mine track between rows of mine roof props 49, 49 on opposite sides of the mine entry but spaced from the opposite ribs of the mine entry. The 15 track-mounted mining machine 12 may be of the type shown in the patent to Levin et al., No. 1,971,862, granted August 28, 1934, for Coal mining apparatus, if the stratum or band of foreign material is at or a short distance above the mine bottom. If the band of foreign material is at a higher elevation, the kerf-cutting mining machine illustrated in the Levin Patent No. 2,021,- 20 664, granted November 19, 1935, may be employed. It should be understood, however, that any other suitable type of kerf-cutting mining machine may be employed provided that the kerf-cutter may be adjusted to the elevation of the dirt band and can operate to swing the turn-table 12' on the vertical axis 12" to effect 25 swinging feeding movement of the cutter bar 14 along an arc concentric with the arcuate working face 13, and provided further that the mining machine can make a rectilinear cut as illustrated by the dotted line 71 in Fig. 1, and a corresponding withdrawal cut can be made on the opposite side of the mine entry. In other words, the track-mounted mining machine is of such type that it may have traction feed along the central track 11 to sump in the kerf cutter 14 recti- 30 linearly along the line 71 in continuation of the rib 72, then be fed arcuately to cut out the dirt band by producing a kerf the inner end of which is parallel to the working face 13, and finally by traction feed producing a rectilinear withdrawal 35 cut in continuation of the rib 73. Inasmuch as the dirt or slate bands may be at any elevation between the floor and the roof, it is preferable to select a kerf-cutting mining machine in which the kerf cutter may have a wide range of adjustment in elevation.

In the operation of the mining machine 12 to cut a kerf at the proper elevation to remove the dirt or slate band, the machine is adjusted with the cutter bar 14 in the position illustrated 55 in Fig. 1, and the kerf-cutting mechanism is

then dumped into the face 13 by operating the truck propelling mechanism of the mining machine along the mine track 11 at a dumping feeding speed. This is followed by arcuate swinging feeding movement of the kerf-cutting mechanism on the vertical axis 12" of the turntable 12' while the truck with the mining machine remains stationary on the main track 11. The rectilinear withdrawal cut is effected at the end of the arcuate feeding movement, by moving the whole mining machine rearwardly along the mine track 11 at a feeding speed, and toward the right as viewed in Fig. 1.

Ordinarily the cutting of a single kerf will be sufficient to remove the entire band of foreign material but in some instances it may be necessary to cut kerfs at two different elevations, for instance above and below a layer or stratum of slate. In such mining machines as those above referred to, endless traveling kerf-cutting chains are mounted for movement around a cutter bar in such a direction as to emerge from the face of the mine vein on the advancing edge of the cutter bar so that the cuttings will be swept from the kerf and permitted to drop downwardly along the face 13 of the mine entry 10.

Positioned directly below the kerf cutter 14 is an arcuate face conveyer 15, which forms the subject matter of the invention herein claimed. This conveyer 15 receives the cuttings as they fall from the kerf under the influence of the endless chain cutter. This face conveyer 15 comprises an arcuate trough 16 mounted on a supporting frame 17 which rests on the mine bottom. On that side of the trough 16 adjacent the working face 13 is pivoted at 18' a receiving chute plate or apron 18 preferably arranged in a plurality of individual sections end to end, as shown in Fig. 1. The plurality of individual sections are separately pivoted as shown at 18' in Fig. 6 to that edge of the trough 16 adjacent to the working face 13. The apron plates 18 have arcuate edges in arcuate alignment and conforming to the curvature of the arcuate face 13 so as to make intimate contact therewith. The apron plates 18 thus contacting with the arcuate face 13 are in position to assure that the cuttings from the kerf cutter 14 will be directed to the trough 16 throughout the various feeding movements of the kerf cutter, including the rectilinear dumping and withdrawal cuts and the intermediate arcuate feeding cut.

The face conveyer 15 is provided with head shafts 19, 19 at the opposite ends thereof. Discharge may be effected from either end of the conveyer, and therefore the conveyer has a discharge head at each end. As the construction of each of the discharge heads of the face conveyer 15 is similar, a description of one will apply to both. Each of said head shafts 19 is provided with a central sprocket 20, as shown in Figs. 1 and 2, and each head shaft 19 is mounted upon the frame 17 in suitable journal bearings 21, 21. By referring to Fig. 1 it will be seen that the axes of the head shafts 19, 19 are fixed relative to the arcuate conveyer trough and converge toward the center of the arcs along which the edges of the trough 16 extend. In other words, the axes of the head shafts 19 are radial relative to the curvature of the trough 16. Between the two sprockets 20, 20 extends a continued double-jointed or universal type conveyer chain 22, the links of which are articulated on pivots the axes of which are at right

angles to each other. The upper and lower runs of the chain 22 are guided and supported by the bottom of the trough 16 and the guide members 23, 23 which are secured to the upper and lower sides of the bottom of the trough 16, as shown in Fig. 6. The upper pair of guide members 23 and the lower pair of guide members 23 have oppositely faced guide grooves into which extend in a re-entrant manner the outwardly extending trough engaging flanges carried by some or all of the links which have vertical pivots. The guide members 23 above and below the trough bottom 16 are arcuate, as shown in Fig. 1, and concentric with the curvature of the inner and outer walls of the conveyer trough 16.

The arcuate guide members 23, 23 guide the conveyer chain 22 along the center of the trough 16 during the upper run, and the under arcuate guide members 23 retain the chain 22 in close proximity to the underside of the conveyer trough 16. In fact, the oppositely facing grooves in the guide members 23 co-operate with the trough engaging flanges of the chain to afford an interlocking connection between the chain and the conveyer bottom both on its upper side and on its lower side.

Laterally extending scraper conveyer flights 24 are connected to certain links at intervals, as shown in Fig. 1. The flights 24 are in fact scraper flights and are held in scraping positions relative to the bottom of the conveyer trough 16 by the interlocking connection between the chain and the guide members 23, 23. It will thus be seen that the interlocking connection between the chain 22 and the guide members 23, 23 on the upper side of the conveyer trough bottom retains the flights in position to scrape along the bottom of the trough 16, and on the underside of the conveyer trough such interlocking connection keeps the conveyer chain together with its flights from sagging.

Midway between the ends of the conveyer 15 and associated with the lower run of the chain 22, I provide three shafts 25, 26 and 27, as shown in Figs. 2 and 3. The shafts 25 and 27 have stationary axes converging toward the center of the arc of curvature of the trough 16. These shafts 25 and 27 are journaled in bearings 28, 28 and 29, 29, respectively, to the frame 17. The shaft 26 is also radially arranged relative to the center of the arc of curvature of the trough 16, and is arranged for vertical adjustment by being journaled to the journal bearing boxes 30, 30 which are slidably vertically in the guides 31, as shown in Fig. 3. Vertical screw adjusting mechanism comprising the vertical screw-threaded rods 32, 32, is provided in association with the boxes 30, 30 and guides 31, to adjust the tension in the chain 22.

As clearly illustrated in Figs. 1, 3 and 6, the shafts 25, 26 and 27 are provided with central sprockets 33, 34 and 35, respectively, about which the lower run of the chain 22 is reeved. The central shaft 26 constitutes the drive shaft for the chain 22 since it carries at that end remote from the coal face, a sprocket 36 which is connected by a sprocket chain 38 to a sprocket on the shaft of the reversible electric motor 37. This is shown in Fig. 2 and diagrammatically in Fig. 3. Obviously, by driving the electric motor 37 in reverse directions, the direction of travel of the endless flight conveyer may be reversed, depending upon whether the cuttings from the kerfs are to be discharged from one end of the

arcuate conveyer trough 16 or the other end.

Adjacent each of the head shafts 19 and located inwardly thereof, I provide a guide and drive shaft 39 journaled in the frame 17 by means of appropriate journal bearings 40, 40. The shaft 39 carries a central sprocket 141 as shown in Figs. 2 and 7. By referring to Fig. 5 it will be seen that the sprocket 141 is in position to guide the chain 22 accurately to and between the guide members 23, 23 on the underside of the conveyer trough bottom. It should be understood that the central sprocket 141 is located at both ends of the conveyer so that the conveyer chain will be directed into the receiving ends of the guide members 23 at both ends of the conveyer trough. In a similar manner the sprockets 33 and 35 are arranged, as shown in Fig. 3, to guide the chain accurately into the receiving ends of the guide members 23 which are interrupted adjacent the driving mechanism illustrated in dotted lines in Fig. 2 and in full lines in Fig. 3.

The shafts 39 also comprise means at both ends of the conveyer for operating rib conveyers 41, 41' which extend along the ribs 72 and 73 to gob piles between the mine roof props 49, 49 and the ribs 72 and 73. The rib conveyers 41 and 41' are similar except that one is right-handed and the other is left-handed, and they are connected to the arcuate conveyer to be selectively driven from either end thereof.

The rib conveyer 41' comprises a frame 42 which forms a trough within which a continuous belt 43 travels over a head pulley 45 and a tail pulley 44. The tail pulley 44 is preferably adjustable for the purpose of varying the tension of the belt 43. The upper run of the belt 43 is supported upon a plate 46, and the lower run is supported upon the idler rollers 47, 47, as shown in Fig. 4.

The receiving end of the conveyer frame 42 is provided with a hopper 48 adapted to guide material to the belt 43 by which it will be conveyed rearwardly and discharged over the tail pulley 44. The discharge end of the conveyer 41' is preferably elevated and supported by one of the roof props 49. By means of a rib wall jack 50 having one end U-shaped to embrace the roof prop 49 and the other end provided with an adjustable anchorage, a horizontal support at adjusted elevation may be provided for the underside of the conveyer 41' near its discharge end, as illustrated in Figs. 1 and 4.

It should be particularly noted that the foreign material, such as dirt or slate cut out by means of the kerf cutter 14 from the dirt band in the mine vein, is delivered into the space between the rib 72 and the roof props 49, 49, and as the mining operations are extended, continuous gobs are formed at the ribs back of the roof props, where they may be left indefinitely, especially if the mining operations are performed to extend an entry.

To drive the pulley 45 at the receiving end of the conveyer 41' and thereby effect the driving of the belt 43, the shaft 51 of the pulley 45 is provided with a sprocket which meshes with a chain 53 and the latter in turn meshes with a sprocket on the transverse shaft 52. The shaft 52 carries at that end remote from the rib 73 a bevel gear 54 which meshes with a bevel gear 55 mounted upon a shaft 56 carried upon appropriate journal bearings in a bracket 57 rigidly attached to the frame 42. The shaft 56 also carries a sprocket 58 with which a chain 59

meshes. The chain 59 also meshes with a sprocket 60 associated with the shaft 39 of the face conveyer 15.

It should be noted that whenever the conveyer 22 of the face conveyer 15 is operated by the motor 37, both of the shafts 39 at opposite ends of the conveyer will be rotated. It is preferable that only the rib conveyer to which material is delivered, be operated when the conveyer 15 is driven, and that the other rib conveyer which is not receiving material, remain idle. Provision has therefore been made, as shown in the drawings, to operate the rib conveyers alternately and automatically, dependent upon the direction of movement of the arcuate conveyer 15. That is to say, when the chain 22 is driven in a direction to effect feeding of cuttings to the rib conveyer 41, the latter shall be operated while the conveyer 41' remains idle, and when material is delivered to the conveyer 41' the conveyer 41 shall remain idle, and that the proper driving connections may be automatically established when the face conveyer 15 is reversed.

As above explained, reversal of the direction of movement of the chain 22 may be effected by reversing the direction of rotation of the motor 37. To provide for the automatic operation of the rib conveyers in accordance with the delivery of cuttings thereto, I provide between the shafts 39 and the sprocket 60 automatic clutches 61, as shown in Figs. 2 and 7. The clutches 61 are reversely connected between the shafts 39 and the sprocket 60 so that only one of these clutches will come into operation to drive the sprocket 60 when the arcuate conveyer is moved in one direction, and the other clutch will come into operation when the arcuate conveyer is driven in the opposite direction.

By referring to Figs. 2 and 5 it will be seen that when the arcuate flight conveyer delivers cuttings to the conveyer 41', the shaft 19 rotates in an anti-clockwise direction while the shaft 39 rotates in a clockwise direction. Now by referring to Figs. 7 and 8 it will be seen that such clockwise rotation of the shaft 39 will effect operation of the automatic ball clutch to transmit rotation from the shaft 39 to the sprocket 60 and thus effect operation of the conveyer 41. At the opposite end of the arcuate conveyer 15 the clutch corresponding to that shown in Figs. 7 and 8, will be released. When, however, the conveyer 15 delivers material to the rib conveyer 41, the latter will be driven and the clutch shown in Figs. 7 and 8 will be reversed so that the conveyer 41 will remain idle.

The detailed construction of the one-way clutch 61 is illustrated in Figs. 7 and 8 of the drawings. Each of the clutches 61 comprises a hub 62 keyed to the shaft 39. The hub 62 is provided with a plurality of notches 63 having therein rollers 64, as shown in Fig. 8 which is a section taken on the line 8-8 of Fig. 7 looking in the direction of the arrows. Surrounding the hub 62 is a casing 65 rigidly attached to the sprocket 60 by means of machine screws 66. The casing 65 has an open face which is closed by a plate 67 rigidly attached thereto by the screws 68. The casing 65 is loosely journaled upon the hub 62 and is held in place by a plate 69 and a screw 70, the latter of which threads into the shaft 39. By referring to Fig. 8 it will be seen that if the shaft 39 is rotated in a clockwise direction, the rollers 64 will effect a wedging action between the notches 63 and the interior sur-

face of the casing 65. Consequently the clutch 61 will become effectively engaged and cause rotation of the sprocket 60 with the shaft 39. Upon rotation of the shaft 39 in a counter-clockwise direction, the rollers 64 will merely roll over the interior surface of the casing 65 without providing any wedging action. Therefore the shaft 39 can turn freely while the sprocket 60 remains stationary.

The clutch associated with the other end of the face conveyer 15 is arranged to operate in a reverse direction and this is effected by providing the notches 63 in reverse positions from that illustrated in Fig. 8 of the drawings, because whenever the shaft 39 is rotated in a clockwise direction, as viewed in Fig. 5, the shaft 39 at the other end of the conveyer will also be operated in a clockwise direction. Therefore the clutch members 62 shown in Fig. 8 should be in reversed positions at the opposite ends of the conveyer 15.

In the operation of the system the kerf cutter 14 is sumped into the faces of the mine vein along the line 71 of Fig. 1, by traction feed rectilinearly along the mine track 11, while the chain cutter is driven in such direction that its left-hand run as viewed in Fig. 1 will emerge from the face of the mine vein and therefore sweep the cuttings from the band of foreign material onto the conveyer 15. During such sumping operation the conveyer 15 should be driven by the motor 31 in such direction as to deliver the cuttings to the rib conveyer 41'. Such direction of operation of the conveyor 15 is maintained during arcuate feeding movement of the kerf cutter 14 toward the other rib 73, and during the withdrawal rectilinear feeding movement from the face of the mine vein.

When it is desired to change conveying the cuttings to the other rib conveyer 41, the kerf cutting operations should start along the rib 73 and then the kerf cutter should be swung on the axis 12" of the turntable 12' in a clockwise direction, and the withdrawal feeding movement should be along the line 71. Previous to such operation of the mining machine kerf-cutting mechanism with the kerf cutter at adjusted elevation, the direction of travel of the cutter chain should be reversed and the bits set accordingly for such reversed travel. The object of the reversal of operation of the chain cutter is to secure emergence of the cutter bits on the advancing edge of the cutter bar to facilitate sweeping of the cuttings from a kerf as the latter is being extended.

When the kerf cutter 14 is being operated from the rib 72 toward the rib 73 or in reverse direction, and the cuttings fed either to the rib conveyer 41' or the rib conveyer 41, the cuttings will be guided by the coal face chute or apron plate 18 into the arcuate trough 16. It should be particularly noted that by reason of the reversal of the clutch members 62 at the opposite ends of the conveyer 15, the rib conveyer to which material is delivered, will be driven while the other rib conveyer remains idle. That is to say, upon reversing the main arcuate conveyer 15 and by reversing the motor 31, the clutch mechanism illustrated in Figs. 7 and 8 will be automatically operated to drive only that rib conveyer to which material is being delivered. When the gob of material formed by delivery of cuttings of foreign material thereto by one

of the rib conveyers becomes unduly large, the other rib conveyer may be automatically brought into operation by reversing the operation of the mining machine and reversing the operation of the main conveyer 15. When the bands of foreign material are relatively thin and the available gob space is relatively large, one of the rib conveyers may be sufficient, but if the gob space is relatively limited or if the bands of foreign material in the mine vein are relatively thick, it is highly desirable to provide both of the rib conveyers 41 and 41', as illustrated in Fig. 1. It is thus evident that a very effective system is provided as illustrated in the drawings, for automatically removing a band of foreign material from a coal vein and conveying it to gobs at the ribs where it will in no way interfere with the mining of coal free from dirt, slate, or other foreign material.

20 The system is also useful to remove coal cuttings, even where there are no dirt bands or bands of foreign material to be removed. In many instances, the kerf cutter in operation produces large amounts of cuttings or slack which must be removed from the room face. The apparatus is useful to remove these cuttings automatically to a position removed from said face.

Obviously those skilled in the art may make various changes in the details and arrangement 30 of parts without departing from the spirit and scope of the invention as defined by the claims hereto appended, and I therefore wish not to be restricted to the precise construction herein disclosed.

35 Having thus described and shown an embodiment of my invention, what I desire to secure by Letters Patent of the United States is:

1. In conveying apparatus, the combination with a frame, of endless conveying means adapted to convey material in reverse directions and discharge it from opposite ends of said frame, drive means for said conveying means including a drive shaft positioned below and intermediate the ends of said frame, conveyer guide means on said frame, means for guiding said conveying means to and from said guide means and said drive means, means for adjusting said drive shaft toward and from said frame to adjust the tension of said endless conveying means, and means including a motor for driving said drive shaft in reverse directions while providing for the aforesaid adjustment thereof.

2. A conveyer comprising a trough formed of a substantially uniform arcuate bottom and arcuate side walls between its ends in a horizontal plane, a sprocket at each end of said trough, a continuous universal conveyor chain having the upper run thereof directly above the lower run, and mechanism including a sprocket meshing with said lower run intermediate the trough ends to drive said chain in reverse directions.

3. A conveyer comprising a trough which curves substantially from end to end in a horizontal plane, head shafts on opposite ends of said trough, conveyer means comprising a universal chain having upper and lower runs and extending over said head shafts, means for guiding the upper run of said chain in a curve through said trough, and means cooperating with the lower run for driving said chain in reverse directions.

NILS D. LEVIN.
